UNITED STATES PATENT OFFICE.

LOUIS HENRY WILLIAMS, OF ST. JOSEPH, MISSOURI.

OIL-CUP.

1,350,196.

Specification of Letters Patent. Patented Aug. 17, 1920.

Application filed March 1, 1920. Serial No. 362,432.

To all whom it may concern:

Be it known that I, LOUIS HENRY WILLIAMS, a citizen of the United States, and a resident of St. Joseph, in the county of Buchanan and State of Missouri, have invented a new and useful Improvement in Oil-Cups, of which the following is a full, clear, and exact description.

My invention relates to improvements in oil cups, and it consists in the combination, constructions, and arrangements herein described and claimed.

An object of my invention is to provide a novel form of oil cup that is adapted to 10 be attached directly to a leaf spring of an automobile, whereby a lubricating oil is fed as needed between the leaves composing the spring.

A further object of my invention is to 20 provide a device of the type described that can be quickly attached to a leaf spring or detached therefrom without the necessity of using any tools.

A further object of my invention is to 25 provide a device of the type described that can be filled while in operative position.

A further object of my invention is to 30 provide a device of the type described that is simple in construction and operation, and is inexpensive to manufacture.

Other objects and advantages will appear in the following specification, and the novel features of the invention will be particularly pointed out in the appended claims.

My invention is illustrated in the accompanying drawings, forming part of this application, in which—

Figure 1 is a side elevation of the device applied to a leaf spring of an automobile.

Fig. 2 is an enlarged section along the line 2—2 of Fig. 1.

Fig. 3 is an enlarged plan view partly in section of the device as applied.

Fig. 4 is a perspective view of a portion 45 of the device.

In carrying out my invention, I provide a pair of separable tray-shaped receptacles 1 and 2. The construction of the receptacles 1 and 2 is identical, and the following description of the receptacle 1, which is illustrated in Fig. 4 of the accompanying drawings, will suffice as a description of both receptacles 1 and 2. I have accordingly indicated corresponding parts in receptacles 1 and 2 by the same reference numerals.

Referring now to Fig. 4, it will be noted

that the receptacle 1 has upright end portions 3 and 4 and upright side portions 5 and 6. Lugs formed on the end portions 3 and 4 are bent outwardly and then downwardly to 60 form hooks 7 and 8. An oil hole 9 is provided in the end portion 3. A continuous strip of packing 10, which has a thickness equal to the height of the side portions 5 and 6, is arranged within the receptacle 1 65 and is disposed along the side portions 5 and 6 and the end portion 4 to provide an oil chamber 11. It will be noted that the oil chamber 11 may be filled through the oil hole 9.

Referring now to Fig. 1, I have shown the device applied to a leaf spring of an automobile, which is composed of leaves 13, 14, 15, 16, 17, 18, and 19, which are in superposed position with respect to one another and are clamped together in any approved fashion as by a clevis (not shown). The receptacles 1 and 2 are adapted to project slightly toward the center of the leaf 13 and the leaf 19, thus preventing the leakage 80 of the contents of the receptacles 1 and 2 at the points of contact with the top and bottom portions of the leaf spring.

The receptacles 1 and 2 are adjustably held against the leaves 13, 14, 15, 16, 17, 18, and 19 by means of tension springs 12 which are hooked at their ends over the hooks 7 and 8.

From the foregoing description of the various parts of the device, the operation 90 thereof may be readily understood. A lubricating fluid is poured through the oil hole 9 until the oil chamber 11 has been filled. The packing 10 will prevent the lubricating oil from leaking from the receptacles and 95 oil will be fed in between the leaves from the oil chamber as needed.

The device is simple in construction and may be quickly adjusted. The construction of the device assures proper lubrication of 100 the leaves of the spring under all conditions.

I claim:

1. A device of the type described comprising a pair of separable tray-shaped oil receptacles, each of said receptacles having at each 105 end an integral lug formed into a hook, and an oil hole in one end, a continuous strip of packing disposed within each receptacle along the side walls thereof, said packing constituting the inner side walls of an oil 110 chamber communicating with said oil hole, and a pair of tension springs adapted to

engage the hooks at each end of said oil receptacles, whereby the latter are held against the side edges of a plurality of superposed leaves which form a spring.

5 2. In combination with a spring formed of a plurality of superposed leaves secured together, an oil cup comprising a pair of separable tray-shaped oil receptacles, each of said receptacles having at each end an integral lug formed into a hook, and an oil

hole in one end, a continuous strip of packing disposed within each receptacle along the side walls thereof, said packing constituting the inner side walls of an oil chamber communicating with said oil hole, and a 15 pair of tension springs adapted to engage the hook at each end of said oil receptacle, whereby the latter are held against the side edges of the superposed leaves in said spring.

LOUIS HENRY WILLIAMS.
